UNITED STATES PATENT OFFICE

109,558

DESIGN FOR A SHALLOW WELL PUMP

Raymond J. Kirkby, Hinsdale, Robert G. Gracey, Oak Park, and Robert E. Schumm and George E. Hansen, Chicago, Ill., assignors to Crane Co., Chicago, Ill., a corporation of Illinois

Application December 24, 1937, Serial No. 73,854

Term of patent 14 years

To all whom it may concern:

Be it known that we, Raymond J. Kirkby, Robert G. Gracey, Robert E. Schumm, and George E. Hansen, the said Kirkby being a subject of Great Britain and the said Gracey, Schumm, and Hansen being citizens of the United States, the said Kirkby residing in Hinsdale, Du Page County; the said Gracey in Oak Park and the said Schumm and Hansen in Chicago, Cook County, State of Illinois, whose post office addresses are 427 S. Washington, Hinsdale; 208 S. Maple Ave., Oak Park; 2104 N. Hamlin Ave., Chicago, Illinois; and 1037 N. Avers Ave., Chicago, Illinois, respectively, have invented a new, original, and ornamental Design for a Shallow Well Pump, of which the following is a specification, reference being had to the accompanying drawings, forming part thereof.

Fig. 1 is a plan view of a shallow well pump showing our new design, the portion being broken away for convenience of illustration.

Fig. 2 is a front view of the pump, the portion being broken away for convenience of illustration.

Fig. 3 is an end view of the pump.

Fig. 4 is an opposite end view of the pump.

The dominant features of the design reside in the portions shown in full lines.

We claim:

The ornamental design for a shallow well pump, substantially as shown and described.

RAYMOND J. KIRKBY.
ROBERT G. GRACEY.
ROBERT E. SCHUMM.
GEORGE E. HANSEN.
